UNITED STATES PATENT OFFICE.

FRANK B. RAE, OF DETROIT, MICHIGAN, ASSIGNOR TO THE DETROIT ELECTRICAL WORKS, OF SAME PLACE.

ELECTRICAL SWITCH.

SPECIFICATION forming part of Letters Patent No. 437,513, dated September 30, 1890.

Application filed March 28, 1890. Serial No. 345,694. (No model.)

To all whom it may concern:

Be it known that I, FRANK B. RAE, a citizen of the United States, residing at Detroit, Wayne county, State of Michigan, have invented certain new and useful Improvements in Electrical Switches, of which the following is a specification.

My invention relates to apparatus for connecting and disconnecting dynamo-machines to and from their working-circuits, and especially where they are operated in multiple arc or parallel circuit. It is well known that when a number of electric generators are connected in multiple arc to feed into the same working-circuit it is necessary to open and close the circuits leading to any one generator in a certain predetermined sequence in order that the currents may pass through the generator without danger of injury to the generator. Under such circumstances, not only are the terminals of the generator connected to the leading or working circuits, but, in order to maintain the generators at substantially a constant potential, they are also connected to a neutral conductor, or what is termed in the art a "buss-wire," and, as this is usually connected directly to the negative brush, if perchance the neutral and positive conductors are closed before the negative conductor, an abnormal current will flow through the armature, which has a tendency to injure or destroy the generator. It has therefore been found necessary under such conditions to close the circuits to include a generator in the series by first closing the negative circuit before the neutral and positive circuits are closed. It sometimes happens that, through inadvertence or otherwise with the ordinary switches in the circuits, the wrong circuit is closed first, and in order to prevent the possibility of such accidents I have devised the switch which forms the subject-matter of this application.

Referring to the accompanying drawings, Figure 1 is a plan view of the switch, with a diagram showing one arrangement of circuits of one of a series of generators feeding into the mains. Fig. 2 is a side view of the switch.

While the switch may be variously constructed and embody the principles of my invention, the preferred form is that illustrated in the

drawings, in which, upon a suitable base A, of non-conducting material, are mounted three sets of terminals B B', C C', and D D'. One of each pair of terminals is connected to the circuits, while the complementary terminal of each pair is connected to one of the circuits of the generator G. Thus the terminal B is connected with the conductor M, which we will assume to be the minus. The terminal C is connected to the neutral or buss wire, and the terminal D is connected with the plus or positive wire of the working-circuit, while on the other hand the terminal B' is connected to the generator at the end of the field-magnet coil F, which is usually placed in series with the armature of the generator. The terminal C' is connected to the brush E', which may be called the "negative brush," and the terminal D' is connected with the brush E, which may be termed the "positive brush" of the generator. Also mounted upon the base, preferably at its end, is a plate H, having lugs h, in which is pivoted the arm I, having a suitable handle J for operating it. This handle is provided with suitable independent connecting-pieces K K' K², arranged transversely to the handle and insulated therefrom in any suitable manner, as by the insulating material L. The ends of the connecting-pieces are preferably bent down, as shown at k, so as to form knife-edges, and the terminals B C D are preferably formed with two upturned edges b b', forming a socket for the reception of the knife-edges. It will be seen that in this arrangement the connector K, being nearer the pivotal point of the lever I, will come in contact with its corresponding terminals before the connector K' will contact with its terminals, and this will complete its contact before the connector K². In this way simply depressing the handle will close the circuits in a certain predetermined order, and when used in the connection illustrated in Fig. 1 all danger of burning or injuring the generator is avoided, as the circuits must be closed properly. The same may be said upon opening the circuits. The connector K² will break the positive circuit before the negative circuit is broken, and in order to switch in and out of circuit any one of a series of generators it is only necessary to move the single

switch-handle and the circuits will be broken or closed properly.

Another advantage is accomplished in the use of the switch illustrated resulting from the transverse arrangement of the connecting-pieces on the arm of the switch and the use of the two terminals to each circuit. In this construction each circuit is broken or closed at two points simultaneously, and thereby the danger of sparking or arcing at the moment of rupture is avoided to a great extent.

While I have described the preferred embodiment of my improved switch and its use in connection with a number of generators feeding into the same circuit, it is evident that the switch may be used in many other connections with advantage and accomplish the same results, and I therefore do not limit myself to the precise construction and arrangement shown.

What I claim is—

1. A switch having three independent sets of terminals and an arm carrying three independent connecting-pieces arranged to con-

tact with the sets of terminals successively, substantially as described.

2. A switch consisting of an insulated base-piece having three sets of terminals mounted thereon and an arm pivoted thereto having three connecting-pieces mounted thereon but insulated therefrom, and arranged to make contact with the terminals successively, substantially as described.

3. A three-point switch consisting of a base-piece having three sets of terminals mounted thereon, each terminal having two upturned edges forming a socket between them, and an arm pivoted to said piece and having three connectors mounted thereon but insulated therefrom, each connector having downwardly-turned ends adapted to engage the terminals successively, substantially as described.

In testimony whereof I have signed my name to this specification in the presence of two subscribing witnesses.

FRANK B. RAE.
